UNITED STATES PATENT OFFICE.

CHAUNCEY W. ABBOTT, OF PITTSBURGH, PENNSYLVANIA, ASSIGNOR TO THE AMERICAN CONDUIT MANUFACTURING COMPANY, OF PITTSBURGH, PENNSYLVANIA, A CORPORATION OF PENNSYLVANIA.

DESIGN FOR A LEFT-HAND-TWISTED ELBOW-BASE FOR FITTINGS FOR ELECTRICAL CONDUITS.

49,688.

Specification for Design.

Patented Sept. 26, 1916.

Application filed August 11, 1915. Serial No. 45,057. Term of patent 14 years.

To all whom it may concern:

Be it known that I, CHAUNCEY W. ABBOTT, a citizen of the United States, residing at Pittsburgh, in the county of Allegheny and State of Pennsylvania, have invented a new, original, and ornamental Design for Left-Hand-Twisted Elbow-Bases for Fittings for Electrical Conduits, of which the following is a specification, reference being had to the accompanying drawing, forming part thereof.

In the drawings, Figure 1 is an elevation illustrating a side view of the ceiling leg and a front view of the side wall leg, Fig. 2 is an elevation illustrating an end view of

a ceiling leg and a side view of a side wall leg, and Fig. 3 is a bottom plan view illustrating a bottom view of the ceiling leg and a bottom or end view of a side wall leg of a left hand twisted elbow base for fittings for electrical conduits, showing my new design.

I claim:

The ornamental design for a left hand twisted elbow base for fittings for electrical conduits, as shown.

CHAUNCEY W. ABBOTT.
